(57) **CLAIM**

The ornamental design of a “spacer for social distancing”, as shown and described.

DESCRIPTION

FIG. 1 is a top right perspective view of a spacer for social distancing, in the fully extended position;

FIG. 2 is a right side orthogonal view thereof;

FIG. 3 is a left side orthogonal view thereof;

FIG. 4 is top orthogonal view thereof;

FIG. 5 is a bottom orthogonal view thereof;

FIG. 6 is a front orthogonal view thereof;

FIG. 7 is a rear orthogonal view thereof;

FIG. 8 is a top right perspective view of the spacer for social distancing of FIG. 1 in the closed position with a strap holding the loose ends together at the right distal end in linear alignment; and

FIG. 9 is a top right perspective view of the spacer for social distancing of FIG. 1 in the closed position with a strap holding the loose ends together at the right distal end in a triangular alignment.

The broken-lines of FIGS. 1-4 and FIGS. 6 and 7 represent a shoulder or hand strap and strap retention rings. The broken-lines of FIG. 5 represent strap retention rings. The broken-lines of FIG. 8 and FIG. 9 depict a shoulder or hand strap and strap retention rings and a strap for holding the distal ends of the stored spacer together. These broken-line portions form no part of the claimed design.
